UNITED STATES PATENT OFFICE.

WILLIAM GRAY, OF HARTFORD, CONNECTICUT, ASSIGNOR TO THE GRAY TELEPHONE PAY STATION COMPANY, OF SAME PLACE.

TELEPHONE-CALL REGISTER.

SPECIFICATION forming part of Letters Patent No. 636,134, dated October 31, 1899.

Application filed October 8, 1898. Serial No. 693,035. (No model.)

To all whom it may concern:

Be it known that I, WILLIAM GRAY, of Hartford, in the county of Hartford and State of Connecticut, have invented certain new and useful Improvements in Telephone-Call Registers, of which the following is a full, clear, and exact description, whereby any one skilled in the art can make and use the same.

My invention relates to the class of telephones in which a record is kept of each use made of the instrument; and the object of my invention is to provide a device of this class in which a coin or a token may be employed for operating the register and in providing a device whereby the coin is retained and the token delivered to the user.

To this end my invention consists in the device as a whole, in the combination of parts, and in the details and their combination, as hereinafter described, and more particularly pointed out in the claims.

Referring to the drawings, Figure 1 is a front view of a set of telephone instruments embodying my invention. Fig. 2 is a front view of the toll-box on enlarged scale. Fig. 3 is a detail front view of the toll-box, on enlarged scale, with the cover removed. Fig. 4 is a detail side view, on enlarged scale, in vertical section, through the toll-box. Fig. 5 is a detail front view, on enlarged scale, of the coin-chute, showing the method of operating the register, the cover-plate being removed. Fig. 6 is a detail end view, on enlarged scale and in section, through the coin-chute. Fig. 7 is a detail top view, on enlarged scale, of the coin-chute and attached parts. Fig. 8 is a detail front view, on enlarged scale, of the coin-chute with the front plate removed and showing the parts in position for operating the register. Fig. 9 is an enlarged detail top view of the spring-fork and hammer-lever engaged.

In the accompanying drawings the letter *a* denotes the backboard, *b* the battery-box, *c* the transmitter, *d* the receiver, *e* the magneto-bells, and *f* the toll-box, of a set of telephone instruments of ordinary construction. The toll-box *f* contains the mechanism for denoting the uses made of the instrument and also for receiving the coins inserted therein for such use.

In the form shown the toll-box *f* consists of

a base *f'*, adapted to be secured to the back-board *a* in close contact with the support for the transmitter *c*, in the present instance the coil-box *c'*, or in any other manner so constructed as to have a metallic connection therewith. The toll-box also consists of a top *f''* and a cover composed of sections *f³* *f⁴* and a pocket *f⁵*, the latter being adapted to receive the coins deposited for the use of the instrument and also having a lug *f⁶* for securing the pocket to the remainder of the toll-box. These sections *f³* and *f⁴* are secured to the base in any suitable manner herein shown, as by means of screws. The pocket *f⁵* has a lug *f⁷* located in the socket *f⁸* on the base.

A bracket *f⁹* extends from the base *f'* and has secured thereto a coin-chute *g*, that leads to a coin-opening *f¹⁰* and a token-opening *f¹¹* in the pocket. A plunger-chamber *g'* is located in the coin-chute and extends laterally thereof. A sectional plunger, consisting of a leader *h* and a follower *i*, is located in this chamber, each of said parts having a reciprocating movement therin. The leader *h* has a handle *h'* and a recessed end *h²*, the former extending through a wall of the plunger-chamber and also through the wall of the toll-box *f* and the latter shaped to fit a token *k* or coin *k'*, the latter being shown in dotted outline.

The end of the follower *i* is inclined, as at *i'*, to receive the thrust of a coin or token and to force such toward the bottom of the plunger-chamber. This follower also bears a connecting-lever pin *i²*, that extends through a slot *g²* and engages the forked end of a connecting-lever *l*, pivoted to the coin-chute at *g³*. The follower also bears a hammer-lever pin *i³*, extending through slots *g⁴* in opposite walls of the plunger-chamber, one end of the pin being engaged with a spring *m*, secured at one end to the coin-chute, and the opposite end of the pin extending in position to strike a hammer-lever *n*, pivoted at *g⁵*.

The connecting-lever *l* bears a lug *l'*, located in position to thrust against the hammer-lever *n* and force it forward. The hammer-lever bears a hammer *n'*, adapted to strike and sound a gong *o*, secured in any suitable position in the form shown to the coin-chute *g*. The upper end of the hammer-lever engages

spring-forks p' , (by which it is normally held,) secured to the end of the register-plunger p , that operates in its reciprocating movement to move the register q , this register and its 5 operation through a reciprocating movement of the plunger being of any well-known and common construction.

The spring-fork may be of any well-known construction, the branching arms of which are 10 of proper shape and strength to retain the hammer-lever. The extreme ends of the arms may be bent away from each other to aid the passage of the hammer-levers between them.

The coin-chute g has a trap g^5 of a size to 15 admit the entrance of a coin, but permit a token to pass over the trap and follow the chute to the token-opening f^{11} , where it may be received by the person using the instrument, it being intended and the device being 20 constructed for the use of a coin smaller in size than that of the token.

In the operation of the device, the parts being at the position shown in Fig. 5 of the drawings, a coin or token is inserted in the 25 coin-opening f^{10} and drops into the plunger-chamber g' . The plunger is now operated by pressure on the handle h' and the coin or token forced forward against the follower i , that retreats against the tension of the spring 30 m . The contact of the coin or token with the sloping surface i' of the follower forces the coin or token downward, which as soon as it reaches the proper position falls through the outlet part of the coin-chute, passing through 35 the trap g^5 if it be a coin or passing through the token-opening f^{11} if it be a token. As the follower i retreats, as described, the pin i^2 , engaging with the connecting-lever l , forces it forward and the lug l' engages the hammer-lever n , held in the grasp of the spring-fork p' , and which is pushed forward, carrying 40 with it the register-plunger p and turning the register forward one step. As the coin or token passes downward through the outlet 45 part of the coin-chute the follower i returns through the impulse of the spring m , causing the hammer-lever pin i^3 to strike the hammer-lever and return the plunger to its former position, the blow also forcing the hammer-lever from the grasp of the spring-fork p' , causing it to strike the gong o , from which 50 it recoils and again enters the grasp of the spring-forks for a repetition of the operation.

The term "traveler" is employed in the 55 claims herein to denote coins or tokens of different construction—as difference in diameter, thickness, or otherwise—and it will be noted that in the device herein described and shown all coins or tokens of one set, all of 60 which said set are of like construction, will be ejected from the machine, while all coins or tokens of another set, all of which set are of like construction, will be retained in the machine.

65 I claim as my invention—

1. In a telephone apparatus, an indicating device, means for operating the indicating

device through the medium of travelers of different construction, means for ejecting the travelers of one set after the operation of the 70 indicating device, and means for retaining the travelers of another set after the operation of the indicating device.

2. In a telephone apparatus, in combination with the sound-transmitting part, a toll-box, 75 an indicator located within the toll-box, means for operating the indicator through the medium of travelers of different construction, means for ejecting the travelers of one set after the operation of the indicating device, and 80 means for retaining the travelers of another set after the operation of the indicating device.

3. In a telephone-toll apparatus, in combination, a sound-indicator, a visual indicator, 85 means for operating both of said indicators through the medium of travelers of different construction, means for ejecting the travelers of one set after the operation of the indicators, and means for retaining the travelers 90 of another set after the operation of the indicating devices.

4. In a telephone apparatus, in combination, an indicator, a sectional plunger having a section operatively connected with the indicator, said sections being adapted to be operatively connected through the medium of 95 travelers of different construction, means for ejecting the travelers of one set after the operation of the indicator, and means for retaining the travelers of another set after the operation 100 of the indicator.

5. In a telephone-toll apparatus, in combination, a sound-indicator, a visual indicator, a sectional plunger having a section operatively connected with both of said indicators, 105 said sections being adapted to be operatively connected through the medium of travelers of different construction, means for ejecting the travelers of one set after the operation of the indicators, and means for retaining the travelers 110 of another set after the operation of the indicators.

6. In a telephone, in combination, an indicating device, a plunger consisting of a leader 115 and a follower arranged to be connected by travelers of different construction, mechanical means for connecting the indicator and follower, means for ejecting the travelers of one set after the operation of the indicator, 120 and means for retaining the travelers of another set after the operation of the indicator.

7. In a telephone, in combination, a plunger having sections adapted to be connected by a traveler, an indicator, a lever bearing a 125 sounding device and adapted to operate the indicator, and connections between a section of the plunger and the lever for operating the latter.

8. In a telephone apparatus, in combination, a plunger having sections adapted to be connected by a traveler, an indicator, a hammer-lever adapted to operate the indicator and bearing a sounding device, and a con- 130

necting-lever connecting a section of the plunger and the hammer-lever.

9. In a coin-controlled telephone, in combination, a plunger, means for operating the plunger through the medium of a traveler, an indicator having a spindle bearing spring-arms, a lever adapted to be detained in the grasp of said arms to operate the indicator and to be disengaged therefrom, and means for operating the lever in the movement of the plunger.

10. In a coin-controlled telephone, in com-

bination, a plunger consisting of a leader and a follower arranged to be connected through the medium of travelers of different construction to impart to the follower the same extent of movement by the operation of each of said travelers, and an indicator operatively connected with the follower. 15
